UNITED STATES PATENT OFFICE

171,641

VEGETABLE JUICING MACHINE OR SIMILAR ARTICLE

Robert D. Dodge, Sierra Madre, Calif.

Application September 8, 1953, Serial No. 26,739

Term of patent 14 years

(Cl. D89—1)

To all whom it may concern:

Be it known that I, Robert D. Dodge, a citizen of the Dominion of Canada, residing in the city of Sierra Madre, in the county of Los Angeles and State of California, have invented a new, original, and ornamental Design for a Vegetable Juicing Machine or Similar Article, of which the following is a specification, reference being had to the accompanying drawing forming a part thereof.

Figure 1 is a front elevation view of a vegetable juicing machine or similar article, showing my new design.

Figure 2 is a side elevation view of the same.
Figure 3 is a top plan view of the same.

I claim:

The ornamental design for a vegetable juicing machine or similar article, as shown.

ROBERT D. DODGE.
